Des. 234,724
Patented Apr. 1, 1975

234,724

CORDLESS ELECTRIC VIBRATOR

John H. Tavel, 17643 Belinda St.,
Encino, Calif. 91316

Filed Jan. 31, 1973, Ser. No. 328,252

Term of patent 14 years

Int. Cl. D28—03

U.S. Cl. D83—1 T

FIG. 1.

FIG. 3.

FIG. 2.

FIG. 4.

FIG. 1 is an isometric view of a cordless electric vibrator embodying my new design;

FIG. 2 is a side elevational view of the same, the opposite side being identical;

FIG. 3 is a bottom plan view of the same;

FIG. 4 is a sectional view of the end cap taken on line 4—4 of FIG. 2.

I claim:

The ornamental design for a cordless electric vibrator, substantially as shown and described.
